UNITED STATES PATENT OFFICE.

JOHN J. MALLOY, OF PORTLAND, OREGON, ASSIGNOR TO THE PACIFIC CAR COUPLING COMPANY, OF OREGON.

CAR-COUPLING.

SPECIFICATION forming part of Letters Patent No. 621,836, dated March 28, 1899.

Application filed June 6, 1898. Serial No. 682,758. (No model.)

To all whom it may concern:

Be it known that I, JOHN J. MALLOY, a citizen of the United States, residing at Portland, in the county of Multnomah and State of Oregon, have invented a new and useful Car-Coupler, of which the following is a specification, reference being had to the accompanying drawings as a part hereof.

My invention relates generally to couplers of the knuckle class, and particularly to the coupler of this type heretofore invented by me and for which Letters Patent of the United States were granted to me bearing date November 2, 1897, No. 593,183; and the object of my present invention is to perfect said coupler in certain particulars and details, as will be apparent from the accompanying drawings.

In such drawings, Figure 1 is a perspective view of a coupler embodying the features of my present invention. Fig. 2 is a transverse section on the line $x-x$ of Fig. 4. Fig. 3 is a rear end elevation of the knuckle, showing the arm and the locking-hook therein pivoted; and Fig. 4 is a plan section on the line $y-y$ of Fig. 2.

The letters designate the parts referred to.

The draw-head a is of the usual type and is provided with a recess a' , adapted to receive the L-arm c of the knuckle b . At the left end of the floor of said recess I provide an inclined approach a'' to automatically lift the hook f , pivoted in the recess e in said arm c , upon the latter entering the recess a' . When the coupler is being closed, said hook f travels along the said incline a'' until it drops into the vertical aperture g . A portion of the surface c' of the back of the arm c is cut away to conform the same to said incline in the floor in the recess of the draw-head. A jog h is cut out in the right wall of the aperture g for the nose f' of the hook f to rest in, and the vertical surface h' of such jog is slightly inclined to cause the upper part thereof to protrude, and the contacting surface of the nose of the hook is correspondingly formed. By this arrangement the pull on the knuckles of interlocking couples will automatically hold the hook in place.

The hook is disengaged by lifting the rod i , 50 which slides in the vertical grooves in the box j , the ring k preventing it from falling through.

In other respects my present invention operates as the coupler heretofore invented by 55 me and above referred to.

What I now claim, and desire to secure by Letters Patent, is—

1. In combination, a draw-head, as a , provided with a recess on its exterior, and a 60 knuckle pivoted to said draw-head and having an arm entering said recess of the draw-head, a hook in the end of the arm, and a vertical aperture for the hook to drop into and lock the knuckle upon the arm thereof 65 having entered said recess, there being an inclined approach in the floor of said recess to automatically lift and guide said hook to said locking-aperture and means for lifting said hook to disengage the knuckle-arm again. 70

2. In combination, a draw-head, as a , provided with a recess, and a knuckle pivoted to said draw-head and having an arm entering said recess of the draw-head, a hook in the 75 end of the arm, and a vertical aperture for the hook to drop into and lock the knuckle upon the arm thereof having entered said recess, there being an inclined approach in the floor of said recess to automatically lift and guide said hook to said locking-aperture and 80 the surface of the said vertical aperture engaging the hook being somewhat inclined to cause the upper part thereof to protrude, and the contacting surface of the nose of the hook being correspondingly formed, for the purpose specified and means for lifting said hook to disengage the knuckle-arm again. 85

3. In combination a draw-head as a provided with a recess, and a knuckle pivoted to 90 said draw-head and having an arm entering said recess of the draw-head, a hook in the end of the arm, and a vertical aperture for the hook to drop into and lock the knuckle upon the arm thereof having entered said recess, there being an inclined approach in the 95 floor of the said recess to automatically lift and guide said hook to said locking-aperture, a jog as h in the right wall of such aperture

for the nose of the hook to rest in, and the vertical surface h of such jog being slightly inclined to cause the upper part thereof to protrude, and the contacting surface of the nose
5 of the hook being correspondingly formed, for the purpose specified, and means for lifting said hook to disengage the knuckle-arm again.

Signed by me, at the city of Portland, county of Multnomah, and State of Oregon, this 24th day of May, 1898.

JOHN J. MALLOY.
